SEWING MACHINE

Carl R. Fox, Indianapolis, Ind., assignor to Real
Silk Hosiery Mills, Inc., Indianapolis, Ind., a
corporation of Illinois

Application May 19, 1948, Serial No. 27,967

3 Claims. (Cl. 112—18)

1

My invention relates to a sewing machine suitable for use in joining together the edges of a flat-knit hosiery blank, and more particularly to that type of sewing machine in which the superposed edges of the blank are advanced between opposed feed rolls or feed cups as they are being seamed. Machines of this type are well known and disclosed, for example, in prior U. S. Letters Patent No. 2,043,749 to H. Hacklander and No. 2,133,229 to C. F. Rubel.

I have discovered that seams produced by machines of the type indicated are frequently rough and uneven in character and possess less elasticity than the body of the stocking. It is accordingly the object of this invention to improve the quality of the seam produced by such machines, and especially to improve the quality of the seam in stocking blanks knit of fine thread. A further object of the invention is to secure in flat-knit stockings a seam which is smoother and embodies stitches of more uniform length than do seams produced in prior sewing machines of which I am aware. Another object is to increase the elasticity of seams in flat-knit stockings. Still another object of my invention is to reduce the possibility of damage to the sewing machine resulting from improper insertion of the blank upon which it is operating.

In carrying out my invention, I add to a machine of the general type disclosed in the patents above mentioned means which operates on the joined fabric edges to apply to such joined edges tension which will aid the feed rolls or cups in advancing the fabric edges past the sewing mechanism. Conveniently, such means takes the form of a presser member resiliently supported from the frame of the machine in position to bear yieldingly against the periphery of one of the feed cups at a point thereon beyond the sewing mechanism, the arrangement being such that the presser member, by resiliently holding the joined fabric edges in contact with the feed cup, causes the application to such joined edges of a tension that tends to draw the fabric edges past the point at which they are in association with the sewing mechanism.

The accompanying drawing illustrates my invention:

Fig. 1 is a front elevation, in partial section, of a sewing machine of the type to which my invention is applicable; Fig. 2 is a fragmental isometric view illustrating the feed cups and the associated presser member, together with a portion of the sewing mechanism; and Fig. 3 is a plan view of the feed cups and associated parts with the fabric edges being joined together.

The machine shown in the drawing comprises a frame 10 having near its top an outwardly projecting hollow arm 11 from which two rotatable feed shafts 12 and 13 depend. At the

2

lower ends, the feed shafts 12 and 13 respectively carry feed rolls or feed cups 14 and 15 mounted in a generally coplanar relationship. The inner shaft 12 is mounted on a stationary axis, while the outer shaft 13 is mounted in a bearing 17 secured to a horizontally disposed rock shaft 18, the arrangement being such that by angular adjustment of the shaft 18 the feed cup 15 can be moved toward and away from the feed cup 14. Preferably, the rock shaft 18 is biased in a counterclockwise direction to urge the outer roll 15 toward engagement with the inner roll 14. To this end, the shaft 18 may be provided with a rigid arm 18' acted upon by a spring 19 and adapted to be moved against said spring by any convenient mechanism (not shown) to separate the feed rolls.

Mounted in the arm 11 above and in general alignment with the outer feed shaft 13 is a shaft 20 connected to the shaft 13 through a universal joint 21. At their upper ends, the shafts 12 and 20 bear meshing gears 22 and 23 one of which is arranged to be intermittently rotated, as by being connected through unidirectional clutch mechanism 24 with an oscillating member (not shown) attached to a reciprocating connecting rod 24'.

The sewing mechanism, with the details of which my invention is not concerned, comprises a reciprocating needle 25, a stitch finger 26, and loopers 27 and 28, all more fully illustrated and described in the issued patents above referred to. In the operation of the machine, the loopers and the needle are operated in timed relation with the intermittently rotating feed rolls to form an over-edge seam uniting the two superposed edges 30 of a flat-knit stocking blank.

The machine as so far described is old. In its operation, the two feed rolls 14 and 15 are separated by rocking the rock shaft 18 in a clockwise direction, the ends of the two fabric edges 30 are superposed and placed between the two feed rolls, and the feed roll 15 is then permitted to move toward the inner feed roll 14 under the influence of the spring 19 until the superposed fabric edges are clamped between the rolls. With the fabric edges secured in such manner, the machine is started, thus causing the feed rolls to rotate intermittently in opposite directions to advance the fabric edges 30; and as such fabric edges advance, the sewing mechanism operates to form a seam including stitch-loops which pass over the stitch finger 26. It will be noted that the stitch finger 26 projects beyond the needle 25 in the direction in which the fabric edges are advanced; and as the stitches constituting the seam include loops passing over the stitch finger, friction between such stitches and the stitch finger tends to oppose advance of the fabric edges. In many instances, especially when the machine

is being used to join the edges of a stocking bank knit from fine thread, such friction may be great enough to interfere with the regular advance of the fabric edges with the result that stitches of uneven length are produced and a relatively inelastic seam of non-uniform quality is created.

As previously indicated, it is the purpose of my invention to produce an elastic seam which will be uniform in quality throughout its length. To accomplish this purpose, I employ means which holds the joined blank edges in contact with the periphery of one of the feed rolls, such means being located beyond the needle 25, and preferably beyond the end of the stitch finger 26, in the direction in which the fabric edges are advanced. Conveniently, such means takes the form of a presser member 32 formed as a portion of a resilient arm 33 having a laterally bent foot 34 secured to the frame 10 of the machine. Beyond the presser portion 32 the arm 33 continues as a finger 35 extending to a point beneath the outer feed roll 15. Inwardly from the presser portion 32, the arm 33 is notched at its lower edge, as indicated at 36 in Fig. 2 to permit the joined fabric edges to move away from the presser portion 32.

As will be clear from Fig. 3, the rear or inner end of the presser portion 32 is generally tangential to the inner feed roll 14, and such presser portion continues outwardly across the space between the two rolls to a point adjacent the periphery of the outer roll 15. Preferably, the outer edge of the presser portion 32 and the upper edge of the finger 35 conform as closely as possible to the peripheral and lower surface portions of the outer roll 15 in order to decrease the possibility that the fabric being sewn will be caught between the arm 33 and the outer feed roll.

A machine with my attachment operates in substantially the same manner as does the conventional overedge sewing machine described in the patents above referred to except that after the joined fabric edges pass beyond the point of association with the sewing mechanism they enter between the presser member 32 and the periphery of the inner feed roll 14. The peripheries of both feed rolls are roughened, as by knurling, to provide a better grip of the fabric edges, while the inner face of the presser member 36 is smooth. As a result, those portions of the fabric edges which are gripped between the presser member 32 and the feed roll 14 are subjected to a feeding effort which tends to draw them out of association with the stitch finger 26 over which stitch loops are formed in the operation of the sewing mechanism. In other words, the feeding effort applied to the joined fabric edges at the presser member 32 overcomes friction between the stitch loops and the stitch finger 26, which friction would otherwise tend to cause the fabric edges to gather adjacent the needle 25 and result in an uneven and relatively inelastic seam.

Ordinarily, initial insertion of the fabric between the feed rolls is performed by gripping the superposed fabric edges at spaced points, applying tension to the fabric between such points, and moving the thus stressed fabric edges upwardly between the separated feed rolls. In the old type machine, it not infrequently happened that an operator making the initial insertion when the needle 25 was advanced would force the fabric edges upwardly far enough to deflect the needle, with the result that when the machine was started the deflected needle would interfere with one

or both loopers and damage would result. In a machine embodying my invention, however, the stretched fabric edges being inserted into the machine will strike the lower edge of the arm 33 before they have been moved upwardly far enough to deflect the needle, and thus the possibility of damage is considerably lessened. As the sewing operation starts, that portion of the presser 32 which extends across the gap between the feed rolls guides the advancing fabric edges to the rear edge of the presser where it will be held against the inner roll 14. The stitch finger 26 is desirably somewhat longer than that used in prior machines, and is preferably curved to follow the periphery of the roll 14 thus aiding in guiding the fabric edges to the point at which they are gripped by the presser 32 and roll 14. The finger 35 on the arm 33 guides the depending fabric and also serves to facilitate the operation of moving the presser 32 away from the feed roll 14 should it be desired to release the fabric edges from between them.

I claim as my invention:

1. In a sewing machine for joining superposed edge portions of a fabric, a frame, a pair of feed rolls rotatably supported from said frame on generally parallel axes, means biasing said rolls toward each other to cause them to grip the fabric edges to be joined, means for rotating at least one of said rolls to advance jointly the fabric edges being gripped between them, sewing mechanism for sewing the fabric edges together as they are so advanced between the rolls, and a presser member associated with one of said feed rolls at a point in the periphery thereof beyond such sewing mechanism, said presser member being resiliently urged toward the associated feed roll to cause the seamed fabric edges to be gripped between such roll and the presser member, said presser member including a stocking-guiding portion extending beneath and inwardly of the other roll in a chordal direction.

2. In a sewing machine for joining superposed edge portions of a fabric, a frame, inner and outer feed rolls rotatably supported from said frame on generally vertical axes and adapted to grip between them superposed fabric edges to be joined, said outer roll being supported for movement toward and away from the inner roll, means for rotating at least one of said rolls to advance fabric edges gripped between them, sewing mechanism for sewing the fabric edges together as they are advanced between the rolls, a resilient arm mounted on said frame and extending outwardly therefrom to a point beneath the outer roll, said arm having an intermediate portion overlying a portion of the periphery of the inner roll and urged theretoward by the resilience of the arm to grip between it and the inner roll the joined fabric edges.

3. The invention set forth in claim 2 with the addition that said presser portion extends generally tangentially of the inner roll to a point closely adjacent the periphery of the outer roll.
